REUSABLE SHIPPING CONTAINER

John L. Rados, San Pedro, Calif., assignor to Harbor Boat Building Company, Terminal Island, Calif., a corporation of California

Filed Dec. 8, 1958, Ser. No. 778,670

26 Claims. (Cl. 206—46)

This invention relates to a reusable container for storing and shipping large, bulky articles, particularly articles of elongate, irregular configuration, such as aircraft tanks and engines, which are often of substantial weight and require shock resistant mounting in a container, as well as ease of insertion into and removal from the container. By reason of bulk, it is also desirable to provide a container, the shipping size of which may be substantially reduced when the contents of the container have been removed and the container is to be re-shipped, empty of cargo, to its point of origin for re-loading and further cargo shipment, and this invention features such a container.

This application is a continuation-in-part of application Serial No. 582,201, John L. Rados, applicant, for a Shipping Container, filed May 2, 1956, now abandoned.

Aircraft are frequently disposed at bases far removed from the source of manufacture of tanks and engines used for replacement therein. The problem of shipment of such tanks and engines is complicated by the fact that the tanks or engines, which must be protected in shipment against excess shock and must also be protected from the elements, are bulky, of irregular shape, and often relatively heavy. Many containers have been designed to protect said objects in shipment, but because the cost of containers to accomplish the desired purposes is so substantial, it is economically unsound to dispose of the containers when they arrive at destination and have been unloaded. On the other hand, in view of the fact that the containers are large and heavy, and also of substantial elongate configuration, reshipment of empty containers to manufacturing sources for reloading and reuse is space-consuming and costly. Ways have been sought constantly to reduce the return shipping size of the empty containers without sacrificing the basic characteristics of loaded containers, and many elaborate methods of accomplishing this object have been proposed from time to time.

It is an object of this invention to provide a strong, shock-resistant shipping container of large, elongate configuration, the over-all size of which may be readily reduced when it is desired to return empty containers to shipping points.

It is a further object of the invention to provide a container of the character described which will protect its contents against water and the elements.

It is another object of the invention to provide a container of the character described which has self-contained loading and unloading means.

It is a further object of the invention to provide a container of the character described which has stacking means to permit firm stacking of containers, one upon the other, in a restricted space.

It is another object of the invention to provide a container of the character described which is equipped with simple and accessible cargo handling devices.

It is a further object of the invention to provide a container of substantial bulk but of relatively light weight

2

which, however, will give ample shock, weather and element protection to its contents.

Another object of the invention is to provide a container which, although bulky, is provided with means for easily but safely removing the end sections therefrom.

It is a further object of the invention to provide a container of the character described, the self-contained loading and unloading means of which are adaptable for securing the contents of the container therein, and also adaptable for separate use apart from the container as a movable cradle.

The container hereinafter described is preferably constructed of plastic and fiber material, but it will be recognized that the body of the container may also be constructed of metal, plywood, or any other substance permitting proper shaping and forming, but at the same time providing rigidity and strength.

In the drawings:

Figure 1 is a perspective view of the container with the end sections thereof removed from the central body section, and showing the cradle partially protruding therefrom.

Figure 2 is a side elevation of the container with the end sections mounted in extended position thereon.

Figure 3 is a view similar to Figure 2 but with the end sections, shown in silhouette, reversed and inserted in the central section of the container.

Figure 4 is an end view of two containers mounted in stacked position, one upon the other.

Figure 5 is a cross-sectional view similar to Figure 2, showing a jet aircraft tank in position in the container.

Figure 6 is an enlarged vertical cross-sectional view taken on the line 6—6 of Figure 5.

Figure 7 is a further enlarged cross-sectional view taken on the line 7—7 of Figure 5.

Figure 8 is an enlarged side elevational view of the cradle removed from the container and with a cutaway jet aircraft tank shown in silhouette resting thereon.

Figure 9 is an enlarged plan sectional view of a portion of the brake element of the cradle taken on the line 9—9 of Figure 8.

Figure 10 is an enlarged view of the end of the cradle removed from the container.

Figure 11 is a substantially enlarged cross-sectional view taken on the line 11—11 of Figure 7.

Figure 12 is a further enlarged view of a detailed construction taken on the line 12—12 of Figure 11.

Figure 13 is a view taken on the line 13—13 of Figure 11.

Figure 14 is an enlarged detailed view of the trip mechanism shown in Figure 11.

Figure 15 is a view taken on the line 15—15 of Figure 7.

Figure 16 is an enlarged sectional view taken on the line 16—16 of Figure 15.

Figure 17 is an enlarged sectional view of a detail taken on the line 17—17 of Figure 15.

Figure 18 is an enlarged sectional view of a detail taken on the line 18—18 of Figure 15.

Figure 19 is an enlarged side elevational view, partly in section, of the mounting of a wheel of the cradle.

Figure 20 is an enlarged cross-sectional cut-away view of a portion of an end section of the container taken on the line 20—20 of Figure 2.

65 The container comprises a center section 10, a rear end section 11, and a front end section 12. Center section 10 is provided with outwardly extending edge flanges 15 and 16. Rear end section 11 has a radially outwardly extending edge flange 17, the outside diameter of which is substantially the same as the outside diameter of edge flange 15 of center section 10, and front end section 12 has a radially outwardly extending edge flange 18, the

outside diameter of which is substantially the same as the outside diameter of edge flange 16 of center section 10.

Elastic rings 20 are designed to fit snugly over the joinder of flange 15 with flange 17, and over the joinder of flange 16 with flange 18, when the end sections 11 and 12 are joined to the center section 10 in the extended position shown in Figure 2, and V-bands 21, having take-up clamps 22, are firmly clamped over the elastic rings 20 and said joined flanges to suspend and hold end sections 11 and 12 in extended position in relation to center section 10, and to provide air-tight, weatherproof, and element-proof joinders between the sections of the container.

The end sections 11 and 12 are also designed to be reversed from the position shown in Figure 2, and to be inserted into the center section 10, as shown in silhouette in Figure 3, when the container has had its cargo unloaded therefrom and is being returned for reloading and reshipment. Consequently, the outside diameter of the end sections 11 and 12 is such that when reversed and inserted into the center section 10, said end sections, held in position in the center section 10 by elastic rings 20 and V-bands 21, will be clear of the inside surface of the center section 10 and also of a cradle 110, hereinafter described, mounted therein. Furthermore, the over-all length of each of the end sections 11 and 12 will be slightly less than one-half of the over-all length of center section 10, so that when in the inverted position mentioned herein, said end sections 11 and 12 will be just clear of each other and properly nested in the center section 10.

For ease in handling, end sections 11 and 12 may be equipped on opposite sides of each such end section with handles such as 25.

Center section 10 has mounted on the outside surface thereof a series of reinforcing rings or T-bars 30. It has been found practical to use four T-bars for each container, spaced as shown in Figures 1, 2 and 3, but it will be understood that a greater or less number of said bars may be used and spaced as desired. T-bars 30 are provided with spurs 31 which rest upon skids 32.

Skids 32 are cross-braced by any suitable means, such as cross-frames 32a, spanning the distance between the skids, and are provided with box channels 33, designed to receive the tires of any standard fork lift, not shown in the drawings. If desired, skids 32 may also be provided with eyes or U-bolts 34 for attaching cargo handling cable, etc. A buffer or bumper bar 35 may also be provided on either side of center section 10, preferably mounted on two or more of the T-bars 30, and positioned to act as a buffer or bumper when the container is being handled by a fork lift.

Mounted on the outside upper lateral surface of the center section 10 are four boxes 40, having flat surfaces 41. The flat surfaces 41 of all four boxes are aligned in a plane just slightly above the horizontal plane of the outside diameters of the flanges 15, 16, 17, 18, and when two or more containers are stacked, as shown in Figure 4, the aligned flat surfaces 41 of the lower container 10 act as a seat or skid rest for the skids 32 of next stacked container 10a.

Each box 40 has projecting upwardly therefrom a spur 42 designed to fit into a corresponding recess 43 in the skid 32 of a container to be stacked thereon, thus to prevent sliding of stacked containers relative to each other. The sides of said boxes 40 are provided also with laterally projecting spurs 44, having eyes 45 designed to receive cargo handling lines or cables 46 shown in Figure 2.

One or more of the boxes 40 may be equipped with a tube 47 extending laterally therein through a port 48, said tube being designed to hold shipping documents, instruction manuals, or other papers or documents, and preferably made waterproof. The tube 47 may have a flanged end 49 to serve to wedge the tube 47 in the port 48, and at the same time to furnish a ready means of grasping the tube 47 for removal from the box 40, or alternatively,

the tube 47 may be mounted in a box 40 by means of screw threads at the flanged end 49 thereof and complementary screw threads in the port 48.

Center section 10 has an opening 50 disposed toward the end thereof, to which end section 12 is to be mounted. As shown in detail in Figure 20, there is mounted in said opening 50 an air valve 51 and a pneumatic tire valve assembly 51a of standard construction. Said air valve 51 is secured in the opening 50 by a thread 52 which is in contact with a complementary thread 53 in a plug 54 having a flange 55, and mounted in the opening 50 by a well-known means, such as thread 56 and locking nuts 57 and 58, so as to make an air-tight connection. By use of means such as nut 59 and gasket 59a, the connection between air valve 51 and plug 54 is air-tight when valve 51 is firmly seated. When valve 51 is loosened, air ports 60 open into the outside atmosphere and air pressure inside the sealed container is released. Pneumatic tire valve assembly 51a is mounted in a threaded opening in nut 59 and has access to the open chamber 60a of air valve 51 and hence to the interior of the container. Air may be introduced into the container by means of said valve assembly 51a, and may be released therefrom by said valve assembly 51a, as well as by loosening valve 51, as hereinabove described.

It will be seen that if the air pressure inside the container is substantial, it would be dangerous to loosen clamp 22 on the front end section 12 in an endeavor to remove V-bands 21 and elastic rings 20 so as to lift front end section 12 from the container and take out the contents of the container at destination without first exhausting the air pressure in the container, because the sudden escape of air pressure around flange 18 might well cause end section 12 to be explosively ejected. In view of its substantial bulk, this could well be disastrously dangerous to persons working on the container to remove its contents.

To prevent such an occurrence said clamp 22 is connected to air release valve 51 by a bracket 66, clamped between air release valve 51 and plug 54 when air release valve 51 is in closed position, and by a short length of chain 65 arranged so that the clamp 22 cannot be removed to permit removal of front end section 12 unless and until valve 51 is opened sufficiently to give play to chain 65 and to allow bracket 66 to be removed from its clamped position between valve 51 and plug 54. Thus air pressure within the container must be exhausted before front end section 12 can be removed from the container.

Inside the center section 10 of the container, and mounted longitudinally on opposite sides thereof and parallel to each other are rails 70, adapted to receive and accommodate rollers 71 which are mounted on a cradle 110, hereinafter described. Said rails 70 extend the entire length of the center section 10. Detailed drawings showing said rails 70 and fittings used in connection therewith are shown in Figures 11-14 inclusive.

The said rails 70 may be connected to the inside surface of the center section 10 of the container by any suitable means such as plates 72, and bolts and nuts 73.

For ease in loading and unloading, the lower flanges 74 of the rails 70 are bent downward, as shown at 75 in Figures 11 and 14, toward the open end of the center section 10, designed to receive the front end section 12.

Said lower flanges 74 have longitudinal openings 76 therein. Pivotally mounted adjacent to and below said openings 76 are trip-bars 77 and 78, connected to each other by a connecting rod 79. The upper ends of said trip-bars 77 and 78 are loosely disposed in said openings 76 and project therethrough. Trip-bars 78 have a lower extension 80 which serves as a hand grip. When the cradle 110 is being loaded into center section 10, rollers 71, in sequence, pass over the trip-bars 78, pivoting them downwardly, and their further progress along the rail 70 is impeded by trip-bars 77, which, by reason of

their correlation with the trip-bars 73 by way of the connecting rods 79, are pivoted upwardly when the trip-bars 78 are depressed. To permit the further passage of the rollers 71 thus impeded, the trip-bars 77 are pivoted downwardly by pushing inwardly on the handle 80.

When it is desired to remove cradle 110 from the container the rollers 71 are moved along the rail 70 until, in sequence, they pass over the trip-bars 77, pivoting said trip-bars 77 downwardly and at the same time pivoting the trip-bars 78 upwardly, thereby blocking the rollers 71. By pulling outwardly on the handle 80, the trip-bars 78 are then pivoted downwardly, allowing the further passage of the rollers along the rail 70. This trip-bar construction is designed to prevent the free, overly rapid movement of the heavy cradle 110 into or out of the container.

Mounted on the rails 70 are blocks 85 designed to secure the cradle 110 against longitudinal movement along the rails 70 when the container is loaded. Details of said blocks are shown in Figures 11 and 12. Any suitable block arrangement is acceptable, but the blocks shown in said Figures 11 and 12 are preferred. They include firm mountings for said blocks on the rails as by bolts 86, and provide an accurate adjustment against movement by set screws 87 mounted on the blocks 85 and designed to impinge on the end of longitudinal frame members 111 of cradle 110, as at 88, shown in Figures 11 and 12.

Blocks 85 are shown in the drawings as mounted on the rails adjacent to the opening of the center 10 facing the end section 12 only. If desired, similar blocks may be provided at the opposite end of the rails 70 to prevent the passage of said cradle 110 beyond the end of the rails 70 adjacent the opening in center section 10 opposite end section 11.

Mounted on the inside surface of end sections 11 and 12 and aligned with rails 70 of center section 10 are plates 90 having hollow cylinders 91 rigidly mounted thereon. Slidably mounted at the openings of center section 120 are pairs of elongate plates 93 having studs or bolts 94 rigidly fastened on the outside edge thereof and projecting upwardly therefrom. Said studs or bolts 94 are of an outside diameter slightly less than the inside diameter of said hollow cylinders 91 and are designed to be loosely disposed in said hollow cylinders 91. Said studs 94 have stop nuts 95 designed to act as a seat for hollow cylinders 91 when said studs 94 are disposed therein. The relative positions of said plates 90, hollow cylinders 91, elongate plates 93 and studs 94 are such that when it is desired to mount either end section on the center section 10, said elongate plates 93 are slidably extended and the end section to be mounted is lifted until hollow cylinders 91 are dropped over studs 94 simultaneously on opposite sides of the container and then seated on stop nuts 95, whereupon the end section so suspended on the sliding elongate plates 93 is impelled toward the center section 10. Upon contact between flange 16 of the center section 10 and flange 18 of the end section, the outside circumference of said flanges 15 and 17, or 16 and 18, as the case may be, will be aligned and ready to receive elastic rings 20 and V-bands 21.

The center section 10 of the container may be equipped with one or a plurality of perforated boxes 100, best shown in Figures 5, 6 and 7. Said boxes 100 are designed to carry a desiccant. In order that said boxes 100 will not interfere with the free passage of the cradle in and out of the container, it is desirable to construct said boxes 100 in a rather flat configuration, preferably following the contour of the inside of the center section 10, and to mount them at the top of the center section 10 by any suitable means.

Cradle 110 is formed of semicircular configuration with parallel longitudinal frame members 111 and arch members 112 spanning the distance between said frame members 111. Mounted on said arch members 112 and extending therebetween parallel with longitudinal frame

members 111 are rods 113. Rollers 71 are mounted in series on said longitudinal frame members 111 by any suitable means, such as by axles 114. Said rollers 71 are preferably disposed adjacent the ends of the horizontal frame members 111, and also at a point substantially forward of the center of said longitudinal frame members 111. Detachably mounted to the inside surface of said longitudinal frame members 111 by shock-proof mountings 115 and disposed substantially parallel to said longitudinal frame members 111 are a set of inner frame members 116. Detachably mounted to the upper side of said frame members 116 and spanning the distance therebetween are arch members 117. By preference, and for ease in loading, said arch members 117 are disposed with one of them mounted at the end of the frame member 116 which will be first inserted into the container, and the second of them mounted in a position between said first arch member 117 and the center of the frame members 116.

20 Detachably mounted to the underside of said frame members 116, disposed inwardly from the ends thereof, and spanning the distance between said frame members 116 are other arch members 118.

25 Details of the detachable mountings for the arch members 118 to the frame members 116 are shown in Figures 17 and 18, which illustrate preferred forms of such mountings. Generally the mountings are accomplished by using threaded bolts 120 having flanged ends 121, screw threads 122 and wing nuts 123. For ease in mounting, said bolts may be disposed in openings 124 in arch members 118, and in open end slots 125 in frame members 116.

30 Pivots mounted to frame members 116 adjacent said open end slots 125, are open slotted washers 126, designed to have the bolts 120 seated in the open slot 127 thereof, and to act as a seat for wing nuts 123 when said wing nuts 123 are tightened on the threads 122.

35 For convenience, the detachable mounting for arch members 118 may be on spurs 128, mounted to the underside of frame members 116, and serving as a downward projection thereof.

40 For ease in manipulating the cradle 110 into and out of the container, the frame members 116 are provided with hand-holds 130 mounted at one end thereof.

45 The cradle may also be equipped with straps or webbing 140, mounted so as to span the distance between frame members 116. At least two sets of said straps or webbing is indicated because the straps or webbing are intended to serve as an additional support for the cargo loaded in cradle 110, and also to serve as an elevating means therefor. Said straps or webbing 140 are securely attached to one frame member 116, but at the opposite side of the cradle, said straps or webbing are wound around a drum 141 rotatably mounted on the frame member 116 on that side of the cradle, as shown in Figures 55 and 16. Means are provided for rotating said drum 141 so as to shorten the slack in said straps or webbing 140, or to lengthen the same, by turning said drum 141 in alternate directions. Such means may include a ratchet wheel 142 on which a drum 141 is securely mounted, the teeth 143 of said ratchet wheel engaging a worm gear 144 rigidly mounted on a shaft 145. A pair of braces 146 is provided for each drum assembly, and said braces are aligned and secured to the frame member 116. The shaft 145 is rotationally disposed in openings 147 in said braces 146. The shaft 145 is also provided with a handle 148, preferably detachable from the shaft 145, and of any acceptable configuration, such as the detachable right-angle handle shown in Figure 15. It will be understood

50 that any suitable handle will be satisfactory, providing, of course, that it is detachable. By turning the handle 148 in one direction, the drum 141 will turn and cause the strap or webbing 140 to be wound around the drum 141, thereby decreasing the slack in the strap or webbing 140, and causing it to come into firm contact with the cargo

In the cradle 110 and either support the cargo in shipment or elevate it upwards from the cradle after removal of arch members 117.

Rigidly mounted on the lower surface of flat plate 169 is a hollow block 300 having a longitudinal bore 301. At the free end of said block 300 is a recessed opening 302, opening into said bore 301. The recess 302 is of smaller diameter than the bore 301. Mounted in said bore 301 is a rod 303 connected to a ring 304 which is normally seated in the recess 302. The rod 303 is biased toward the collar 168 by a spring 305, seated in said bore 301. The block 300 is spaced from collar 168, and the rod 303 projects from the block 300 through the open end of the bore 301 toward said collar 168. Mounted on said rod 303 is a tongue 306, the outer end of which, in normal locked position, is seated in a recess 307 in collar 168 when the caster wheel 160 is in position aligned with bar 113, or in a recess 308 when caster wheel 160 is in position at an angle to bar 113. Cut in said collar 168 is groove 309 designed to slidably receive tongue 306 when tongue 306 is not in position in recess 307 or in recess 308.

The operation of said block and ring assembly on each caster wheel assembly is as follows:

When it is desired to have the caster wheel 160 in straight position, parallel to rod 113, the ring 304 is seated in the recess 302 and the tongue 306, impelled forward by the action of spring 305 on rod 303, is seated in recess 307, and the caster wheel 160 is locked in that position. If it is desired to release the locking action and permit free movement of caster wheel 160 in any direction, ring 304 is pulled out of recess 302, given a half-turn, and allowed to seat against the outer surface 310 of block 300, whereupon tongue 306 is withdrawn from recess 307 and is free to slide freely in groove 309.

If it is desired to lock caster wheel 160 in a position at an angle to bar 113, tongue 306 is aligned with recess 308, and ring 304 is turned until it is seated in recess 302, whereupon tongue 306 will be impelled into recess 308 and caster wheel 160 will be locked in said position.

Rotationally mounted on each of the bars 113 adjacent to the ends thereof are caster wheels 160. Said wheels 160 may have pneumatic tires 161. The axle 162 of each wheel 160 is rotationally mounted by recognized means to caster frame 163. Caster frame 163 is rigidly mounted to an angle iron 164, and the combined caster frame 163 and angle iron 164 are rotationally mounted on one end of a vertical axle 165, preferably hollow, which has a thread 166 and a lock nut 167 mounted thereon at the lower extremity thereon to act as a seat for angle iron 164.

Striated on angle iron 164 is a collar 168, and mounted on said collar 168 is a flat plate 169, bored at opposite sides thereof to receive threaded bolts 170. In turn, mounted on said flat plate 169 is a second plate 171, having complementary bores to receive said threaded bolts 170. Mounted on opposite ends of said threaded bolts 170 externally thereof are lock nuts 172 and 173.

Rigidly mounted at its lower end to plate 171 is hollow vertical collar 180. Said hollow vertical collar 180 is rigidly mounted at its upper end to horizontal sleeve 181, which in turn is rotationally mounted on bar 113. Horizontal sleeve 181 is secured against lateral movement along bar 113 by ring collars 182.

Mounted on the sleeve 181 is flat plate 183 which is bored to receive pin 184. Pin 184 has mounted on its upper end hand-wheel 185. Pin 184 is impelled toward bar 113 by spring actuated means (not shown), and fits into holes (not shown) in bar 113, which are complementary to the hole bored in plate 183 and are spaced on bar 113 to allow locking of the sleeve 181 against rotational movement on bar 113 either in the upright position shown in some detail in Figure 8, or in the folded position shown in Figure 7.

Pivottally mounted on caster frame 163 opposite the rotational mounting of the axle 162 is a brake pedal 200.

Brake pedal 200 has at one end thereof adjacent to pivotal mounting 201, a camming surface 202. At the opposite end of brake pedal 200 is roughed surface 203 which serves as a firm foothold.

5 Camming surface 202 is of angled configuration, having a lower surface 203, and upper surface 203a, designed to impinge upon brake shoe 204. Mounted on said brake pedal 200 at approximately the center thereof and extending downwardly therefrom is an extension 205 10 having at its lower extremity an opening 206 in which is firmly disposed one end of a cable 207.

Brake shoe 204 is pivotally mounted at its upper end to caster frame 163 and is normally impelled rearwardly and away from caster wheel 160 by a spring 210, which 15 is seated in a recess 211 in angle iron 164 and against which brake shoe 204 impinges.

Brake shoe 204 has a braking surface 215 designed to hold against the outside circumference of caster wheel 160.

20 Brake shoe 204 has mounted thereon a roller 220, and cable 207 passes from opening 206 in extension 205 under and around said roller 220 in an upwardly direction, generally through hollow vertical axle 165 and collar 168, plate 169 and plate 171. Cable 207 then passes 25 through an opening 221 inside of hollow vertical collar 180 and is led by any suitable means, such as clamps 222, upwardly along the arch rings 112 and along the surface of frame members 111 to approximately the center thereof. It will be understood that said cable 207 is 30 preferably a flexible metallic cable disposed in a protective tube 223.

At substantially the center of said frame member 111, the end of cable 207 from one caster wheel assembly at one end of the cradle approaches the end of another 35 cable 207 from the caster brake assembly at the other end of the cradle. For ease of mounting and adjustment, said cable ends may terminate in turnbuckles 224. Turnbuckles 224 are mounted by normal means to opposite ends of an elongate plate 225, rotationally 40 mounted at approximately the center thereof to said frame member 111. Rigidly mounted to said elongate plate 225 at substantially the center thereof, is brake handle 226.

The action of said brake mechanism is as follows: 45 The brake shoe 204 is normally impelled away from the caster wheel 160 by the spring 210, and caster wheel 160 is normally able to turn freely on its axle 162. When it is desired to brake said caster wheel 160 in both the forward caster wheel assembly and the rearward wheel assembly, brake handle 226 is moved in either a clockwise or in a counterclockwise direction, whereon the elongate plate 225 is turned, causing a pull to be exerted on the cables 207. The pull on cables 207 exerts a downward pull on brake pedals 200, causing camming surface 203 50 to impinge on brake shoe 204 and bias it toward caster wheel 160, at which point braking surface 215 impinges on caster wheel 160 and brakes it.

The same braking action can be obtained by stepping on rough surface 203 with sufficient force to counteract 55 the action of spring 210.

When it is desired to release the brake, handle 226 is 60 returned to its normal vertical position, whereupon elongate plate 225 is in position approximately parallel to frame member 111, and the pull tension on cables 207 is relieved. At the same time foot pedals 200 are permitted to rotate clockwise on pivots 201 to free camming surface 203 from its abutment with brake shoe 204 and allow spring 210 to bias brake shoe 204 clear of 65 caster wheel 160, until camming surface 203a comes in contact with brake shoe 204, whereupon further movement of brake shoe 204 away from caster wheel 160 is arrested, but caster wheel 160 is free to turn, clear of 70 contact with braking surface 215.

75 Bars 113 may also be equipped with one or more brackets 230, having openings 231 designed to hold tools

and parts of the device, when the cradle is partially dismantled, as hereinafter described.

The cradle may also be equipped with a bridle or shaft 240 mounted by any suitable means to one of the arch rings 112, as shown cut-away in Figure 8.

The container is used as follows: When the container is to be loaded with the article to be shipped therein, say a jet tank, the center section 10 of the container is placed on its skids in a convenient place on the floor or loading dock. The rear end section 11 is then aligned with the rear end of center section 10 and the pair of elongate plates 93 are moved outwardly from the center section 10 to their full extent.

The rear end section 11 is then lifted until the hollow cylinders 91 on the rear end section 11 are in position directly over the studs 94 on the elongate plates 93 of center section 10. The rear end section 11 is then lowered so that the studs 94 are disposed in the hollow cylinders 91 and the hollow cylinders 91 are seated on the stop nuts 95. The rear end section 11, so suspended, is then moved forward until flange 17 of rear end section 11 abuts against flange 15 of center section 10, at which point the outside circumferences of flange 17 and flange 15 are in substantial alignment. The joinder of the two flanges 17 and 15 is then covered by an elastic band 20, and a V-band 21, with its clamp 22, is disposed over said elastic band 20 and adjusted and tightened to form an airtight fit.

Cradle 110 is then loaded with the jet tank to be shipped. To accomplish this the caster wheels 160 of cradle 110 are lowered and the brake mechanism of cradle 110 is set to hold the caster wheels 160 against movement. The upper arches 117 are not mounted, but the inner frame members 116 and the lower arches 118, rigidly mounted thereon, are placed in the cradle, and the shock-proof mountings 115 are adjusted and tightened. Ample slack is put into the straps or lengths of webbing 140. The jet tank is then placed in the cradle, with the longitudinal center of the tank at substantially the longitudinal center of the cradle 110. The upper arches 117 are then mounted on and fastened to the inner frame members 116, and then the straps or lengths of webbing 140 are adjusted to form additional seats for the jet tank and to serve as additional shock protection.

Cradle 110, so loaded, is then aligned with the open end of center section 10 of the container, the brakes having been released, and the cradle is placed in position for mounting on tracks 70 of center section 10 of the container. The cradle is moved toward the container until the first pair of rollers 71 are in the tracks 70. The cradle is then moved into center section 10 of the container until the trip mechanism combination of elements 76-80 prevents further forward progress.

At this point the first pair of caster wheels 160 are turned inwardly and elevated so as to permit further free passage of the cradle 110 into the center section 10 of the container. The trip bars 77 are then released and the container is moved further into the center section 10 of the container, the second pair of rollers 71, mounted in approximately the center of the cradle 110 being placed in the tracks 70, and, after release of the trip mechanism described above, the progress of the cradle 110 into the center section 10 is continued until the trip mechanism is again struck by the last pair of rollers 71. The second pair of caster wheels 160 is then in turn turned inwardly and elevated. The trip mechanism having then been released, the cradle 110 is further inserted into center section 10 of the container until its progress is impeded by the stops at the rear end of the tracks 70. Another pair of stops 85 is then affixed to the forward end of the tracks 70, and the cradle 110 is thus locked against longitudinal movement on the tracks 70.

The cradle 110 and its cargo, having thus been secured in the container, the front end section 12 is then aligned

with center section 10 of the container and in turn elevated, mounted on studs 94, and pushed forward until the flange 18 of the front end section 12 abuts against flange 16 of center section 10, whereupon an elastic band 20 is placed about the joinder of the flanges, and the V-band 21 and its clamp 22 are placed around the elastic band 20 and tightened to form an airproof fit, in the manner of the joinder of the rear end section 11 to the center section 10, heretofore described.

10 The loaded container is then ready for shipment. If desired, air under pressure may be injected into the container by means of the valve 51a. As above stated, for the sake of safety, the air valve assembly is connected to the clamp 22 of the V-band 21 which encircles the joinder of the front end section 12 with center section 10, in order to prevent the inadvertent removal of the front end section 12 before the air under pressure in the container is released, as hereinabove described.

The loaded container is then moved by lift, truck or crane to a position for storage or shipment. If it is to be stacked on another loaded container, it is lifted above the other container until the spurs 42 of the other container are in line with the recesses 43 in the skid 32 of this container, and then lowered into position with 25 the spurs 42 disposed in the recesses 43.

On arrival at destination, the container is placed on level ground, a floor or loading dock and air under pressure in the container is released in the manner hereinabove described, the clamp 22 at the joinder of the front end section 12 with the center section 10 is loosened, and the V-band 21 and elastic band 20 are removed from flanges 16 and 18, and the front end section 12 is then pulled away from center section 10, and lifted off the studs 94. The front end section 12 is then moved aside.

The forward stops 85 are then removed from the tracks 70, and cradle 110 is grasped by handholds 130. The cradle 110 is then pulled forward in a direction to remove it from the center section 10 until the first pair 40 of rollers 71 contact the trip assembly. At this point the forward pair of caster wheels 160 are dropped into vertical position, the trip mechanism is released, and cradle 110 is pulled further away from the center section 10, riding on the first pair of caster wheels 160, but 45 still resting on rollers 71 on tracks 70. When the last pair of rollers 71 meet the trip mechanism, the other pair of caster wheels 160 are dropped into vertical position. The trip mechanism is then released and cradle 110 is fully removed from the center section 10.

50 The loaded cradle may then be moved into position under an aircraft which is to be loaded with the jet tank cargo which is resting in the cradle. For ease in handling, the upper arches 117 are removed from the frame members 116, and, if desired, the drums 141 are turned by means of the handles 148 and related mechanisms to taunt the straps or webbing 140, and lift the jet tank into better position for handling and lifting into the aircraft.

Upon removal of the jet tank cargo from the cradle 60 110, the frame members 116 are removed from their position inwardly parallel to frame members 111 by loosening the shock mountings 115, and are then placed in position above and still parallel to frame members 111, and fastened in that position. The straps or 65 webbing 140 are again slackened and all removable projecting articles, such as handles 148, and shock mountings 115, are removed and placed in the openings 231 in brackets 230, or mounted along frame members 111 in position out of the way. If a shaft or bridle 70 240 has been provided for cradle 110, it too is removed from its operating position at one end of the cradle and mounted parallel to one of the bars 113 at the outside of the cradle at a position at which it will not interfere with the free loading of the cradle into the center section 10 of the container. The container so dismantled

is aligned with the forward open end of center section 10, and inserted therein in the same manner as it was inserted when loaded. The stops 85 are again placed in position to prevent the longitudinal movement of the cradle along the tracks 70.

The center section 10 of the container is then in condition to receive the inverted end sections 11 and 12, and the said end sections are reversed and inserted into center section 10 in the telescoped position shown in Figure 3.

The elastic bands 20 and the V-bands 21, with their clamps 22, are then placed in position around the reversed joinder of the flange 16 with the flange 18, and the flange 15 with the flange 17, and tightened to suspend the end sections in the positions shown in said Figure 3. If desired, the open part of the end sections 11 and 12 may be covered with a suitable cover, a plastic cover being suggested for that purpose, but the use of such covers is optional and not shown in the drawings.

The container is then in condition for reshipment to a source of manufacture of jet tanks or other container cargo, and for reuse as a cargo container.

While the instant invention has been shown and described herein in what is conceived to be the most practical and preferred embodiment, it is recognized that departures may be made therefrom within the scope of the invention, which is therefore not to be limited to the details disclosed herein but is to be accorded the full scope of the claims so as to embrace any and all equivalent devices.

Having thus described my invention, what I claim as new and desire to secure by Letters Patent is:

1. A reusable shipping container comprising: an open-ended center section; cup-shaped end sections removably mounted in extended position on opposite ends of said open-ended center section; means for reversing the extended position of said end sections and inserting each end section in said center section when the center section is empty of cargo; a cargo cradle mounted in said center section so as to be slidably removable therefrom; and wheels on said cradle mounted so as to swing into retracted position when the cradle is mounted in said center section, and so as to swing into carrying position when the cradle is removed from said center section.

2. A reusable shipping container comprising: an open-ended center section; cup-shaped end sections removably mounted in extended position on opposite ends of said open-ended center section; a cargo cradle mounted in said center section so as to be slidably removable therefrom; outwardly extended flanges at the open ends of said center section; an outwardly extended flange at the open end of each said end section having an external surface formed to match the external surface of one of the flanges on said center section; removable means for clamping said flanges together; and means for reversing the extended position of each of said end sections and inserting each of them in said center section comprising an internal surface on the flange of each said end section, formed to match the external surface of one of the flanges on said center section; and removable means for clamping said flanges together.

3. A reusable shipping container as defined in claim 2, wherein said means for clamping flanges together and said means for reversing the position of said end sections and inserting each of them in said center section comprise: elastic rings covering and binding matched and mated flanges; V-bands removably mounted on said elastic rings; and securing clamps mounted on said V-bands.

4. A reusable shipping container as defined in claim 3, including wheels on said cradle mounted so as to swing into retracted position when the cradle is mounted in said center section, and so as to swing into carrying position when the cradle is removed from said center section; and releasable brakes operatively connected to said wheels.

5. A reusable shipping container as defined in claim 4, including locking means mounted on said cradle so as to lock said wheels in predetermined positions.

6. A reusable shipping container comprising: an open-ended center section; cup-shaped end sections removably mounted in extended position on opposite ends of said open-ended center section; means for reversing the extended position of said end sections and inserting each end section in said center section when the center section is empty of cargo; a supporting skid frame mounted on said center section so as to seat said center section in a horizontal resting position; and a cargo cradle mounted in said center section so as to be slidably removable therefrom.

7. A reusable shipping container as defined in claim 6, including slotted openings in said skid frame for receiving the tires of a fork lift truck.

8. A reusable shipping container as defined in claim 6, including U-bolts mounted on said skid frame for receiving cargo hoisting cables.

9. A reusable shipping container as defined in claim 6, including open-end recesses in the bottom of said skid frame disposed so as to receive extending spurs of a second container on which said first container is stacked.

10. A reusable shipping container as defined in claim 6, including skid rests positioned on the top of said center section so as to receive a supporting skid frame of a second container stacked upon said first container.

11. A reusable shipping container as defined in claim 10, including upwardly extending spurs mounted on said skid rests, and adapted to be disposed in openings in the undersurface of the supporting skid frame of said second container.

12. A reusable shipping container as defined in claim 10, including eyes mounted on said skid rests for receiving cargo hoisting cables.

13. A reusable shipping container comprising: an open-ended center section; cup-shaped end sections removably mounted in extended position on opposite ends of said open-ended center section; means for reversing the extended position of said end sections and inserting each end section in said center section when the center section is empty of cargo; a cargo cradle mounted in said center section so as to be slidably removable therefrom; cargo carrying straps spanning said cradle; and means for adjusting the length and tautening said straps.

14. A reusable shipping container comprising: an open-ended center section; cup-shaped end sections removably mounted in extended position on opposite ends of said open-ended center section; means for reversing the extended position of said end sections and inserting each end section in said center section when the center section is empty of cargo; parallel rails mounted on the inner side walls of said center section and extending longitudinally therein; and a cargo cradle having rollers mounted on said rails so as to be slidably removable from said center section.

15. A reusable shipping container as defined in claim 14, including releasable stops mounted on said rails so as to arrest the free movement of said rollers on said rails.

16. A reusable shipping container comprising: an open-ended center section; cup-shaped end sections removably mounted in extended position on opposite ends of said open-ended center section; means for reversing the extended position of said end sections and inserting each end section in said center section when the center section is empty of cargo; an air valve mounted in one end section for introducing air under pressure into and discharging air from the container; and a cargo cradle mounted in said center section so as to be slidably removable therefrom.

17. A reusable shipping container as defined in claim 16, including releasable locking means for said end section and the center section, mounted on said air valve.

and adapted to prevent the removal of said end section from contact with said center section until air under pressure in said container has been released.

18. A reusable shipping container comprising: an open-ended center section; cup-shaped end sections removably mounted in extended position on opposite ends of said open-ended center section; means for reversing the extended position of said end sections and inserting each end section in said center section when the center section is empty of cargo; and a cargo cradle mounted in said center section so as to be slidably removable therefrom and having a frame of parallel lateral longitudinal frame members, downwardly curving arcuate members spanning the distance between said lateral frame members and rigidly mounted thereto, upwardly curving arcuate members also spanning the distance between said lateral frame members and detachably mounted thereto, parallel lateral longitudinal bar members and wheels mounted on said bar members so as to swing into retracted position when the cradle is mounted in said center section, and so as to swing into carrying position when the cradle is removed from said center section.

19. A reusable shipping container as defined in claim 18, including shock-proof mountings disposed between said parallel lateral longitudinal frame members.

20. A reusable shipping container as defined in claim 18, including tool-holding brackets mounted on said bar members.

21. A reusable shipping container as defined in claim 18, including hand-holds mounted at one end of said cradle.

22. A reusable shipping container comprising: an open-ended center section; cup-shaped end sections removably mounted in extended position on opposite ends of said open-ended center section; means for aligning said end sections for mounting on said center section comprising pairs of elongate plates, the members of each pair being slidably mounted on opposite sides of said center section adjacent an open end thereof, a stud mounted on each of said plates and extending upwardly therefrom, and hollow cylinders formed to overlie said studs and mounted on said end sections adjacent the open ends thereof in position opposite related spurs when said end sections are placed in position for mounted joinder with said center section; means for reversing the extended position of said end sections and inserting each end section in said center section when the center section is empty of cargo; and a cargo cradle mounted in said center section so as to be slidably removable therefrom.

23. A reusable shipping container comprising: an open-ended center section; a desiccant holder mounted on the inside wall of said center section; a tube paper container mounted externally on said center section; cup-shaped end sections removably mounted in extended position on opposite ends of said open-ended center section; carrying handles mounted on said end sections; means for

reversing the extended position of said end sections and inserting each end section in said center section when the center section is empty of cargo; and a cargo cradle mounted in said center section so as to be slidably removable therefrom.

24. A reusable shipping container comprising: an open-ended center section; outwardly extended flanges at the open ends of said center section; parallel rails mounted on the inner side walls of said center section and extending longitudinally therein; cup-shaped end sections removably mounted in extended position on opposite ends of said open-ended center section; outwardly extended flanges at the open ends of said end sections, each having an external surface formed to match the external surface of one of said flanges on said center section when said end section is in extended position, and having an internal surface formed to match the said external surface of said center section flange when said end section is reversed and inserted in said center section; elastic rings covering and binding matched and mated flanges; V-bands removably mounted on said elastic rings; securing clamps mounted on said V-bands; and a cargo cradle having rollers mounted on said rails so as to be slidably removable from said center section.

25. A reusable shipping container as defined in claim 24, including wheels on said cradle mounted so as to swing into retracted position when the cradle is mounted in said center section, and so as to swing into carrying position when the cradle is removed from said center section.

26. A reusable shipping container as defined in claim 25, wherein said cargo cradle comprises a frame of parallel lateral longitudinal frame members, downwardly curving arcuate members spanning the distance between said lateral frame members and rigidly mounted thereto, upwardly curving arcuate members also spanning the distance between said lateral frame members and detachably mounted thereto, and parallel lateral longitudinal bar members on which said wheels are mounted.
